LOCATION INDICATOR

Sylvia Young, Indianapolis, Ind., assignor to The S. K. Smith Company, Chicago, Ill., a corporation of Illinois

Filed Apr. 3, 1958, Ser. No. 50,325

Term of patent 3½ years

(Cl. D25—1)

The dominant features of my design reside in the portions shown in full lines.

I claim:

The ornamental design for a location indicator, as shown and described.
